UNITED STATES PATENT OFFICE.

DANIEL BICE, OF SPENCERVILLE, OHIO.

FENCE-POST.

SPECIFICATION forming part of Letters Patent No. 747,361, dated December 22, 1903.

Application filed July 25, 1902. Serial No. 116,981. (No model.)

To all whom it may concern:

Be it known that I, DANIEL BICE, a citizen of the United States, residing at Spencerville, in the county of Allen and State of Ohio, have 5 invented a new and useful Fence-Post, of which the following is a specification.

The invention relates to improvements in fence-posts.

The object of the present invention is to 10 improve the construction of fence-posts and to provide a simple and comparatively inexpensive one of great strength and durability adapted to be readily constructed of wrought-iron or other suitable material and capable 15 of enabling a fence to be rapidly erected.

The invention consists in the construction and novel combination and arrangement of parts hereinafter fully described, illustrated in the accompanying drawings, and pointed 20 out in the claim hereto appended.

In the drawings, Figure 1 is a perspective view of a portion of a fence provided with posts constructed in accordance with this invention. Fig. 2 is a detail view illustrating 25 the manner of attaching the upper ends of the inclined braces to the corner-posts. Fig. 3 is a plan view of the corner-post. Fig. 4 is a detail sectional view illustrating the manner of securing the lower end of the upright 30 portion of the post to the horizontal arm of the inclined inner or rear portion.

Like numerals of reference designate corresponding parts in all the figures of the drawings.

35 1 designates a fence-post composed of an upright front portion 2 and an inclined rear portion 3, forming a transverse brace and provided at its bottom with a horizontal arm 4, forming the base of the post and designed 40 to be embedded in the ground, as indicated in Fig. 1 of the drawings. The upright portion 2, which may be constructed of any suitable material, preferably consists of a piece of wrought-iron, and its lower end 5 is reduced and secured in a slot 6 of the arm 4, 45 preferably by upsetting the reduced portion against the lower face of the arm to form a head. The inclined portion 3, which is arranged at the back of the post, is formed integral with the horizontal base, both parts being constructed of a single piece of wrought-iron or other suitable material. The upper

and lower portions of the inclined back or brace of the post are provided with quarter-bends 7 and 8, and the intermediate portion 55 of the brace 3 is arranged edgewise to the front portion, as shown. The upper end 9 of the inclined rear portion of the post is secured to the front portion by means of a bolt 10 or other suitable fastening device, and a brace 60 11 may have its upper end interposed between the upright front portion of the post and the inclined rear portion or brace of the same. The brace 11 extends longitudinally 65 of the fence, and its upper end is perforated 70 to receive the said bolt 10. The lower end of the brace 11 is arranged upon an anchor or support 13, consisting of a block or stone and designed to be arranged with its upper face at the surface of the ground. The lower 75 portion of the inclined longitudinal brace is connected with the upright portion of the post by means of a wire 14 or other suitable connection. One end of the wire 14 passes through a perforation 15 of the lower portion 80 of the inclined brace 11, and the other end of the wire extends through a similar perforation of the upright portion of the post. The wire 14 may be secured to the post and the brace in any desired manner.

The inclined braces 11 may be arranged at intervals along the fence, and they may be omitted when not required.

The corner-post is supported by a pair of longitudinal braces 11, having their upper 85 ends interposed between the inclined rear portion of the post and the upright front portion of the same and connected at their lower ends with the upright portion of the post by connecting-wires 14 and are supported on 90 blocks, as clearly shown in Fig. 1.

Horizontal fence-wires or runners 16 are preferably secured to the post by means of staples 17, receiving the fence-wires and arranged in slots of the upright portion of the 95 post and having their sides spread at the inner face of the said upright portion; but any suitable means may be employed for securing fence-wires or other fencing material to the post.

It will be seen that the fence-post is exceedingly simple and inexpensive in construction, that it possesses great strength and durability, and that it may be readily con-

structed of wrought-iron, bar metal, or other suitable material.

What I claim is—

A fence-post comprising an inclined rear brace provided with a forwardly-extending base portion, an upright portion connected at its lower end to the base and at its upper end to the rear brace, and an inclined side brace pivotally attached at its upper end to the upper portion between the same and the rear

brace, the pivotal axle of the side brace serving also as a means for attaching the rear brace to the upright.

In testimony that I claim the foregoing as my own I have hereto affixed my signature in the presence of two witnesses.

DANIEL BICE.
